US0D1095511S

(12) **United States Design Patent** (10) **Patent No.:** **US D1,095,511 S**
(45) **Date of Patent:** **** Sep. 30, 2025**

(54) **MAGNETIC PHONE HOLDER**

(71) Applicant: **Shenzhen Baseus Technology Co., Ltd**, Shenzhen (CN)

(72) Inventors: **Fei Zhou**, Shenzhen (CN); **Linsong Chen**, Shenzhen (CN); **Junru Yue**, Shenzhen (CN)

(73) Assignee: **Shenzhen Baseus Technology Co., Ltd**, Shenzhen (CN)

(**) Term: **15 Years**

(21) Appl. No.: **29/920,368**

(22) Filed: **Dec. 11, 2023**

(30) **Foreign Application Priority Data**

Aug. 1, 2023 (CN) 202330487006.6

(51) **LOC (15) Cl.** **14-06**

(52) **U.S. Cl.**

USPC **D14/253**; D12/415
